UNITED STATES PATENT OFFICE.

HERBERT L. WILLIAMS, OF AKRON, OHIO, ASSIGNOR TO THE WILLIAMS FOUNDRY AND MACHINE COMPANY, OF AKRON, OHIO, A CORPORATION OF OHIO.

QUICK-OPENING HEAD FOR HORIZONTAL VULCANIZERS.

1,197,702.

Specification of Letters Patent. Patented Sept. 12, 1916.

Application filed March 28, 1914. Serial No. 827,813.

To all whom it may concern:

Be it known that I, HERBERT L. WILLIAMS, a citizen of the United States, and a resident of Akron, county of Summit, and State of Ohio, have invented a new and useful Improvement in Quick-Opening Heads for Horizontal Vulcanizers, of which the following is a specification, the principle of the invention being herein explained and the best mode in which I have contemplated applying that principle, so as to distinguish it from other inventions.

The present improvements relate to quick opening heads for vulcanizers, and particularly to an easily operated and constructed head or cover for closing a horizontally disposed vulcanizer. The ordinary horizontally disposed vulcanizer consists of a cylindrical casing open at one end in which the tires or other articles to be cured are received and a cover for the open end of the casing, such cover being, in different constructions, supported either upon rollers or by means of a suitable crane, as the weight of the same is considerable. Either method of support is inconvenient and is not easy to operate, and the present invention has been designed to provide a conveniently operated and simple head which can be formed as a part of the vulcanizer chamber and can be adjusted so that it will always tightly close the open end of such chamber irrespective of the amount of wear upon the members from which the head is supported.

To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of the various mechanical forms in which the principle of the invention may be used.

In said annexed drawing: Figure 1 is an end elevation of a horizontal vulcanizer provided with a head constructed in accordance with the present invention; Fig. 2 is a side elevation taken from the right of Fig. 1; Fig. 3 is a vertical section showing a modified form of cover, and Fig. 4 is an elevation on an enlarged scale of a detail shown in Fig. 1.

In Figs. 1 and 2 there is shown a cylindrical casing 1 which is horizontally mounted upon suitable supports 2 and is open at one end. Attached to the casing adjacent to such end is a bracket 3 provided with vertically disposed sockets 4 and 5 in which is pivotally mounted a short shaft 6, the latter resting upon a thrust bearing, consisting of a button 7 of suitable material which may be adjusted vertically to compensate for wear by means of a screw 8. The precise construction of this bracket is not of material importance as any suitable form may be used. Attached to such short shaft 6 is an arm 25 which for stability is forked, either portion of the fork being attached to the shaft by means of set screws 9. The arm 25 extends horizontally from the shaft 6 and pivotally attached to such arm, about a substantially horizontal axis, is a cover 10 adapted to close the open end of the casing 1. The open end of the casing is provided with radially disposed spaced lugs 11 and the cover 10 is similarly provided with radially disposed spaced lugs 12 adapted to engage beneath the lugs 11 upon a slight rotative movement of the cover about its axis. The cover is first swung into its closing position at which time the lugs 12 slip between the lugs 11. A suitable bar or rod may then be inserted in sockets 13 attached to the cover, when it will be a simple matter to rotate the cover into its locked position, the two sets of lugs on the cover and casing forming interlocking means which are adapted to secure the cover firmly in the closing position, which is, of course, highly necessary as a high steam pressure is used in the cylinder during the vulcanizing operation. It is unnecessary to state that the usual packing means are preferably provided between the casing and cover for rendering this joint steam tight.

It will be obvious that the weight of the cover will tend to wear away the pin which serves as an axis for the same, and if this pin is worn awry unevenly the cover will not seat tightly in the casing. In order to maintain the cover in such a position that the plane of the cover, (when the latter is in its closing position) will be parallel to the plane of the open end of the casing, I provide means for adjusting the cover. Such means include a vertically disposed arm 15

attached to the arm 25, such arm 15 being provided with a bar 16 in which are adjustably mounted screws 19 having conical points 26 to contact a gib 17 which may thus be held against a lug 18 attached to the cover. The gib 17 may thus be adjusted by means of the screws 19 and this action will force the upper part of the cover either away or toward the vertical arm as may be desired. In this way the cover can always be kept in a tight and effective condition irrespective of the wear on its axis.

The majority of the horizontal vulcanizers now in use are provided with bolts 20, shown 15 in Fig. 3, which are pivoted and are adapted to engage in slots 21 formed in the cover which is placed in position to close the open end of the casing. The present type of cover can be used on this form of casing in place of the old cover, if the construction is modified, as shown in Fig. 3. Under 20 these conditions it is necessary to remove the old cover and to substitute for the same a collar 22 which is provided with the slots 21 and may thereby be bolted to the casing. This collar 22 is formed as is the open end 25 of the casing shown in Fig. 1, that is it is provided with radially spaced lugs 23 beneath which the lugs on the cover are adapted to engage. The cover will, of course, be mounted in this construction in substantially the same way as in Figs. 1 and 2, being supported upon a suitable bracket attached adjacent to the open end of the casing.

35 In order to facilitate the opening and to secure a tight closing of the vulcanizer, I provide means which insure that the cover 10 will be stopped either in position for the lugs 12 on the cover to engage directly beneath the lugs 11 on the casing, or in such position that the lugs 12 are between the lugs 11, depending on the direction in which the cover is moved. These means preferably comprise spaced stop pins 30 and 31 mounted 40 in the lug 18. When the cover is moved into the closing position (see Fig. 1) the stop 30 engages the bar 16 thus causing the cover to stop in such a position that the lugs 12 are beneath the coating lugs. The stop 45 31 acts similarly upon movement of the cover in the opposite direction to cause the lugs 12 to stop between the lugs 11.

Other modes of applying the principle of my invention may be employed instead of 55 the one explained, change being made as regards the mechanism herein disclosed, provided the means stated by any of the following claims or the equivalent of such stated means be employed.

60 I therefore particularly point out and distinctly claim as my invention:—

1. In a vulcanizer the combination with a horizontally disposed casing forming the vulcanizing chamber, said casing being open 65 at one end, of a cover for such open end,

said cover being pivotally mounted about both a horizontal and a vertical axis, means adapted to adjust the inclination of said cover with respect to the vertical, and locking means mounted on said cover and said casing and adapted to lock the former to the latter in closed position. 70

2. In a vulcanizer the combination with a horizontally disposed casing forming the vulcanizing chamber, said casing being open 75 at one end, of a cover for such open end, said cover being pivotally mounted about both a vertical and a horizontal axis, means for adjusting the vertical position of said cover, other means adapted to adjust the inclination of said cover with respect to the vertical, and locking means mounted on said cover and said casing and adapted to lock the former to the latter in closed position. 80

3. In a vulcanizer, the combination with a horizontally disposed casing forming the vulcanizing chamber, said casing being open 85 at one end, of a bracket attached to said casing adjacent such open end, an arm pivotally mounted upon said bracket about a vertical axis, a cover for such open end of said casing, said cover being pivotally mounted upon said arm about a horizontal axis, interlocking means on said cover and said casing adapted to engage upon partial rotation of said cover when in closed position, and means adapted to adjust said cover to a position in which the plane of said cover is parallel to the plane of such open 90 end of said casing. 95

4. In a vulcanizer, the combination with a horizontally disposed casing forming the vulcanizing chamber, said casing being open 100 at one end, of a bracket attached to said casing adjacent such open end, an arm pivotally mounted upon said bracket about a vertical axis, a cover for such open end of said casing, said cover being pivotally mounted upon said arm about a horizontal axis, interlocking means on said cover and said casing adapted to engage upon partial rotation of said cover when in closed position, and means adapted to adjust said cover to a position in which the plane of said cover is parallel to the plane of such open 105 end of said casing, said last named means including a projecting lug on said cover and an adjustable plate mounted on said arm and bearing against such lug. 110

5. In a vulcanizer, the combination with a horizontally disposed casing forming the vulcanizing chamber, said casing being open 115 at one end, of a bracket attached to said casing adjacent such open end, a cover pivotally mounted upon said bracket about a vertical axis, and also about a horizontal axis, means for adjusting said cover both as to height and inclination with respect to the vertical, and interlocking means mounted on said cover and said casing adapted to 120

lock the former to the latter upon partial rotation of the former when in closed position.

6. In a vulcanizer the combination with a horizontally disposed casing forming the vulcanizing chamber, said casing being open at one end, of a bracket attached to said casing adjacent such open end, an arm pivotally mounted upon said bracket about a vertical axis, adjusting means for varying the vertical position of said arm upon such axis, a cover pivotally mounted upon said arm about a horizontal axis, means adapted to adjust the inclination of the cover with respect to the vertical, and interlocking means mounted on said cover and said casing adapted to lock the former to the latter upon partial rotation of the former when in closed position.

20 7. In a vulcanizer, the combination with a horizontally disposed casing forming the vulcanizing chamber, said casing being open at one end, of a bracket attached to said casing adjacent such open end, an arm pivotally mounted upon said bracket about a vertical axis, a cover for such open end of said casing, said cover being pivotally mounted upon said arm about a horizontal axis, interlocking means on said cover and said casing adapted to engage upon partial rotation of said cover when in closed position, a second arm attached to said first-named arm, said second arm being substantially parallel to said cover, and two stop pins mounted on said cover and adapted to cooperate with said second arm to limit such partial rotation of said cover to stop the same upon engagement of said interlocking means.

25 8. In a vulcanizer, the combination with a horizontally disposed casing forming the vulcanizing chamber, said casing being open at one end, of a bracket attached to said casing adjacent such open end, an arm pivotally mounted upon said bracket about a vertical axis, a cover for such open end of said casing, said cover being pivotally mounted upon said arm about a horizontal axis, interlocking means on said cover and said casing adapted to engage upon partial rotation of said cover when in closed position, a second arm attached to said first-named arm, said second arm being substantially parallel to said cover, and two stop pins mounted on said cover and adapted to limit such partial rotation of said cover to stop the same upon engagement of said interlocking means.

30 9. In a vulcanizer, the combination with a horizontally disposed casing forming the vulcanizing chamber, said casing being open at one end, of a bracket attached to said casing adjacent such open end, an arm pivotally mounted upon said bracket about a vertical axis, a cover for such open end of said casing pivotally mounted upon said arm about a horizontal axis, said arm having an extension, and means attached to said cover and engaging such extension, said means being adapted to adjust the vertical position of said cover.

Signed by me, this 25th day of March, 1914.
